UNITED STATES PATENT OFFICE.

CHARLES A. BUTLER, OF SPOKANE, WASHINGTON.

MOVING-PICTURE MACHINE.

1,152,283.

Specification of Letters Patent. Patented Aug. 31, 1915.

Application filed August 18, 1914. Serial No. 857,284.

To all whom it may concern:

Be it known that I, CHARLES A. BUTLER, a citizen of the United States, and a resident of Spokane, in the county of Spokane and State of Washington, have invented a new and Improved Moving-Picture Machine, of which the following is a full, clear, and exact description.

This invention relates to improvements in moving picture machines, and has for an object to provide an improved construction of frame and associated parts for moving the intermittent sprocket of the machine up and down without interfering with the time of the shutter with relation to the lens or with the intermittent movement of the sprocket.

Another object of the invention is to provide an improved construction designed to reduce to a minimum the lost motion between the intermittent movement of the sprocket and the shutter, said structure operating for producing this result without interfering with the movement of the frame when adjusting the intermittent sprocket.

In carrying out the objects of the invention a supporting plate is provided which acts as a stationary frame which may be mounted upon a suitable base. To this plate or frame is connected the apertured plate which guides the film. Pivottally mounted on this plate is a swinging housing which carries the various sprocket wheels for feeding the film, whereby when the housing is swung either up or down the film will be correspondingly moved in respect to the apertured plate. Connected with the swinging frame is a lever construction for actuating the frame. In order to lock the frame in any of its adjusted positions suitable clamping screws are provided which may be sufficiently loose to allow a movement of the housing when positively moved by the lever, whereby the housing may be moved at any time either while the film is passing through the apertured plate or while the film is stationary.

In the accompanying drawings Figure 1 is a transverse vertical section through a machine embodying the invention; Fig. 2 is a side view of the machine with part of the pivotally mounted housing broken away; Fig. 3 is a side view of the machine shown in Fig. 1, the same being the opposite side to that shown in Fig. 2.

Referring to the accompanying drawings

by numeral, 1 indicates a supporting plate provided with a base 2 which may be secured to any kind of a support. Connected with the plate 1 in any desired manner are boxes 3 and 4 which are designed to accommodate the opposite end of the film 5, this part of the device forming no part of the invention. The plate 1 is cut away at 6 and 7 (Fig. 3) for accommodating the sprocket wheels 8, 9 and 10, the film guiding wheel 11 and power shaft 12. It will be observed that the plate 1 is thus provided with an extension 13 having, preferably, an upstanding portion 14 to which an apertured plate 15 is connected, the apertured plate 15 being of any desired or preferable structure which is held stationary by plate 1. Plate 1 also carries the lens holding device 16 which is supported in any desired manner, as for instance by strap 17. At the forward part of the plate 1 a pivotal pin 18 is provided which pivotally supports the housing 19, which housing carries the various film guiding and moving sprocket wheels, and also which carries the various operating mechanisms as more clearly shown in Figs. 1 and 2. The power shaft 12 has connected therewith a suitable crank 20 which when operated moves the power gear 21, which power gear operates a plurality of gearing and other mechanism in chamber 22, moving the sprocket wheels 8, 9 and 10.

It will be observed from Fig. 1 that the power gear 21 meshes with pinion 23, and with a second pinion 24, which second pinion is rigidly secured to shaft 25. Shaft 25 has a gear wheel 26 rigidly secured thereto which meshes with pinion 27 rigidly secured to shaft 28. Pinion 27 meshes with gear 29 which is of the same size as gear 26, whereby shaft 30 rigidly secured to gear 29 rotates at the same speed as shaft 31 secured to pinion 23, the intermediate pinion 24 being of the same size as pinion 23. This causes the sprocket wheels 8 and 10 to rotate at the same speed. The intermediate sprocket 9 is connected with shaft 32, which shaft is connected with shaft 28 through a suitable intermittent movement 33 which may be of the Geneva type or any other type desired wherein the number of rotations of shaft 32 will be the same as shaft 30 though the movement will be intermittent. Shaft 28 has not only pinion 27 secured thereto, but also a beveled gear 34 which meshes with a beveled pinion 35, which pinion is rigidly

secured to shaft 36. Shaft 36 is suitably journaled in the outer end of housing 19, and has rigidly connected thereto a shutter 37 which may be of any desired type, but preferably of a shape substantially as shown in Fig. 1. From Fig. 1 it will be observed that the shutter 37 is almost a half disk, whereby there is substantially the same amount of light as darkness. It will be noted that the gear wheel 34 is larger than pinion 35, whereby the shutter will rotate faster than the shaft 32, preferably making three revolutions for each intermittent movement of the shaft 32, whereby the light is shut off while the picture is moving, and twice in addition, to minimize the flicker.

The housing 19 is swung or pivotally mounted upon the journal 18 adjacent to the shutter, and is guided in its movement by the clamping screws 38 and 39. The clamping screws 38 and 39 extend through slots 40 and 41, respectively, in the extensions 42 and 43 of housing 19, as clearly shown in Fig. 2. In order to produce a proper swinging or pivotal movement of the housing 19 a link 44 is pivotally connected with extension 43, which link is pivotally connected in turn with the lever 45, which lever is pivotally mounted at 46 on the stationary plate 1. By pressing downwardly upon the outer end of lever 45 the film will be moved upwardly, and by moving the lever 45 upwardly the film will be moved downwardly, regardless of whether or not the machine is in operation. This raising and lowering of the film will cause a proper framing of the picture at any time without varying or changing in the least any of the adjustments or the distances between the various sprocket wheels or other means operating the film. By this construction and arrangement the operator may turn crank 20 with one hand and at the same time move lever 45 with the other hand so as to either quickly or slowly adjust the machine so as to instantly frame the picture.

What I claim is—

1. In a moving picture machine of the character described, a stationary plate carrying an apertured gate and a lens, a swinging frame pivotally mounted on said stationary plate, said pivotal mounting being an appreciable distance in front of the apertured gate and the lens, whereby the part of the frame opposite the gate, when moved pivotally a short distance, will travel substantially in a straight line past the gate, said swinging frame carrying the various moving parts of a moving picture machine, including the sprocket wheels whereby the feeding sprocket and the take-up sprocket are movable with the frame, as well as the intermittent sprocket, and means for swinging said frame on its pivotal support.

2. In a moving picture machine of the

class described, a stationary plate formed with a forwardly extending portion, a movable frame formed with a forwardly extending portion, means for pivotally connecting both of the forward ends of said forward portions, mechanism arranged on said moving frame at the rear part thereof for moving a film, said mechanism including a gear wheel, a pinion meshing with said gear wheel, a shaft connected with said pinion and rotated thereby, said shaft extending to a point beyond the front end of the forwardly extending portion of the frame, a shutter connected with said shaft and rotated thereby, and means for moving said film-operating mechanism up and down without substantially affecting the position of the shutter.

3. In a moving picture machine of the class described, a stationary plate carrying the apertured gate and the lens, and a swinging frame carrying the mechanism for moving the film, said swinging frame being pivotally connected with said stationary frame so as to move the intermittent sprocket wheel in a direction substantially away from or toward the apertured gate and the other sprocket-wheels in proportion, and means for moving said swinging frame.

4. In a moving picture machine of the class described, a stationary plate carrying the apertured gate and the lens, a swinging housing, means for pivotally connecting one end of said housing with said stationary plate, whereby the opposite end of the housing will move substantially parallel with the direction of travel of the film through said gate, the moving parts of the machine including the shutter and all of the sprocket-wheels being mounted on said housing, means for swinging said housing, and means for frictionally clamping said housing in position so as to frictionally resist said swinging movement.

5. In a moving picture machine of the class described, a stationary plate, a stationary apertured gate, a lens, a pivotally mounted housing carrying the moving parts of the picture machine, a journal member for pivotally mounting said housing to said stationary plate, whereby the intermittent sprocket wheel arranged on said housing may be moved in a direction parallel to the movement of the film through said apertured gate, means for actuating said swinging housing, and means for locking the swinging housing in any of its adjusted positions.

6. In a moving picture machine of the class described, a stationary plate, a stationary apertured gate, a lens, a pivotally mounted housing carrying the moving parts of the picture machine including the shutter and the sprockets, a journal member arranged adjacent the shutter for pivotally

mounting said housing on said stationary plate, whereby the intermittent sprocket wheel arranged on said housing may be moved in a direction substantially parallel to the movement of the film through said apertured gate, and means for locking the pivotally mounted housing in any desired position.

In testimony whereof I have signed my name to this specification in the presence 10 of two subscribing witnesses.

CHARLES A. BUTLER.
